UNITED STATES PATENT OFFICE.

ROBERT A. BOSWELL, OF WASHINGTON, DISTRICT OF COLUMBIA.

AMPLIFYING-HORN FOR TALKING-MACHINES.

999,954.

Specification of Letters Patent. Patented Aug. 8, 1911.

Application filed May 11, 1910. Serial No. 560,582.

To all whom it may concern:

Be it known that ROBERT A. BOSWELL, a citizen of the United States of America, residing at Washington, District of Columbia, 5 has invented a new and useful Amplifying-Horn for Talking-Machines, of which the following is a specification.

The invention about to be set forth and claimed belongs to the art of acoustics, and 10 it particularly pertains to a new and useful sound conveying tube having a compound curved tubular member arranged at a point between the free ends thereof, and adapted for use upon talking machines and the like.

15 The novel principle of this invention is to support the arm and horn in the compound curved tubular member, in order to have free movements, whereby the stylus of the sound box may accommodate itself to 20 the sound waves, or annular indentures of the record.

A further feature of the invention is to so 25 connect and support the arm and the horn of this particular form as to allow the arm to be readily lifted from the record, in order to dispose it slightly to one side thereof, or to raise the horn vertically. When the horn is raised, the same is easily and readily supported within a portion of the compound 30 curved tubular member by friction. It is also understood that the arm may be supported in the member by friction. The horn, as shown in Figure 2, may be so arranged as to swing laterally, as well as vertically, but, as shown in Figure 1, the lateral 35 movement of the horn is dispensed with.

In the exposition of this specification, a particular design of machine is adhered to but the invention is not to be confined to 40 this special design. Its reduction to practice may require certain changes and alterations which the right is claimed to make, provided such changes and alterations are comprehended by the appended claims.

45 The sound conveying tube proper only consists of three parts, and so supported, as above stated, as to perform all the necessary functions required upon a talking machine.

50 Further features and the arrangement of parts will be hereinafter set forth and pointed out in the claims.

Referring to the drawings,

Figure 1 is a side elevation of a talking machine, showing an amplifying horn applied thereto, and provided with the com-

ound curved tubular member, for the support of the free moving parts of the horn.

Figure 2 is a vertical sectional view through the compound curved tubular member, which is shown in Figure 1, with the 60 exception that the members 29 and 30 are eliminated.

Figure 3 is a sectional view on line 3—3 of Figure 2, disclosing the connection between the compound curved member and its 65 support.

Figure 4 is a detail sectional view, showing a portion of the compound curved tubular member, connected to its support by means of screws. 70

Figure 5 is a detail sectional view of a modified form of the mounting of either the compound curved member 6 or the curved member 21.

As to the drawings, 1 denotes the casing of 75 a talking machine, containing the usual mechanism (not shown) for rotating the table carrying the records.

2 represents a bracket secured to one side of the casing for supporting the amplifying 80 horn 3.

The amplifying horn comprises the horn proper 4 and the reproducer arm 5, which are movably supported within the compound curved tubular member 6. The tubular 85 member is detachably supported upon the bracket 2, as shown at 7. The compound curved tubular member is provided with a projection 8, which has lateral projections 9, which, together with the projection 8, 90 form an approximately T-shaped member, which is dove-tailed or received within the recess 10 of the bracket 2. This recess 10 conforms to the shape of the T-shaped projection, and is designed to fit neatly and 95 snugly therein, there not being sufficient friction to prevent the ready removal of the said T-shaped projection.

In Figure 4, the compound curved tubular member, at its lower portion, is slightly 100 enlarged, as shown at 12, which is provided with threaded recesses 13. The bracket 2, in Figure 4, is penetrated by a pair of screws 14, which are threaded into the recesses 13, in order that the tubular member 105 may be readily and detachably supported upon the bracket 2.

In Figure 1, the horn proper, at its restricted portion, terminates into a curved neck 15, which is telescopically received

within one of the curves 16 of the compound tubular curved member 6. The friction between the curved neck 15 and the inner circumference of the curved portion 16 of the tubular member is just sufficient to allow the horn 4 to be easily moved and readily supported when moved.

In Figure 2, however, the curved neck 15, is detachably connected to the horn 4, by means of a threaded connection, as shown at 17. For instance, the portion 18 of the horn may be provided with possibly one, two or three threads, in order to engage approximately the same number of threads upon the inner circumference of the neck 15, as at 19.

The reproducer arm 5, at its larger portion, terminates into a neck 20 (which is similar to the neck 15) but curved in the opposite direction. The neck 20 is supported telescopically within the curved portion 21 of the compound curved tubular member, with sufficient friction to allow the arm to rest and be easily supported in the position desired.

The neck 20, at the lower portion 22, and upon its inner circumference, may be provided with one, two or three, or as many threads as desired, as shown at 23, in order to be engaged by a similar number of threads 24 of the reproducer arm 5. By this connection, for instance between the neck 20 and the reproducer arm 5, the arm may be allowed to move laterally, in order that the stylus may accommodate itself to the annular indentures or sound waves of the record. By curving the two necks 15 and 20 in the manner shown, in order to conform to the contour of the compound curved tubular member, the arm and horn may be held in various adjusted positions, as shown clearly in dotted lines.

It will be noted, upon examining the drawings, that the sound emanating from the sound box will have a smooth and clear passage, until it reaches the atmosphere. It will further be noted that this construction of amplifying or sound conveying horn is a marked improvement upon all others now patented or upon the market, and, furthermore, the connecting of the arm and horn may be readily accomplished, by taking one in each hand and inserting them telescopically within the curved portions of the compound curved tubular member, and adjusting them in their proper co-relative positions. Furthermore, all ball joints or similar connections are all dispensed with. From the foregoing, it will be readily understood how the various parts of the sound conveying or amplifying horn are connected and operated.

In Figure 1 the compound curved member at each end is provided with a leaf spring 27, so shaped or formed as to engage

notches or depressions 28 of the curved portions or necks 15 and 20, in order to hold the reproducer arm and horn in various raised positions. In Figure 2 these features are dispensed with.

In Figure 1 the compound curved member 6 is provided with a downwardly projecting arm 29, to which the upwardly and forwardly extending arm 30 (which projects from the lower portion of the neck 20) is pivoted, in order to cause the reproducer arm to swing exactly concentric with the curved portion 21 of the member 6, so that the stylus may more accurately accommodate itself to the sound waves of the record. In Figure 2 these arms 29 and 30 are eliminated.

In Figure 4, however, the curved portion 16 of the compound curved member is dispensed with, and the curved portion 21, at the portion 21^a, terminates into the horn proper 4. In Figure 4 the curved portion 21 receives the neck 20, as shown in dotted lines. As shown in Figures 2 and 4, the neck 20 is sufficiently long, so that the portion 20^b thereof may approximately hook over the portion 6^a of the compound curved member, whereby as the stylus is playing upon the record, the reproducer arm may be readily supported. This hooked arrangement is the same throughout the raising or lowering of the reproducer arm.

If it is so desired, the horn 4 proper may be provided with a pivotal arrangement in Figure 1, similar to that of the reproducer arm.

In Figure 5, the curved portion 21 is provided with an annular flange 32, below which a cylindrical portion 33 is formed. This cylindrical portion is received within a cylindrical opening 34 of the angular portion of the support 2, whereby the curved portion 21 may swing laterally. This curved portion 21 may or may not terminate into the horn proper 4. The lower portion of the cylindrical portion 33 receives a screw stud 35, which prevents the curved portion 21 from being removed from the cylindrical opening of the angular portion of the support 2. The neck 20, in Figure 5, is similar to that shown in Figures 1 and 2 and designated by the same character. The connections between the neck 20 and the reproducer arm 5 are also similar and denoted by the same characters.

Having set forth the invention, what is claimed as new and useful is:—

1. A supported compound curved tubular member; and an arm and horn supported thereby to have vertical movements.

2. A curved tubular member; a reproducer arm correspondingly curved and movable longitudinally and telescopically in the curved portion of the member, whereby said arm is adapted to have vertical movement.

3. A compound curved member; and a reproducer arm and horn correspondingly curved and received thereby to have longitudinal movements therein; said arm and horn being supportable in various positions.
4. A compound curved member; a horn and a reproducer arm correspondingly curved, said members being telescopically united to have vertical movements.
- 10 5. A compound curved tubular member; a reproduced arm having a neck portion threaded thereto; said neck portion being received within the lower curve of the compound curved member, and a horn having a curved neck received within the upper curve of the compound curved member to move longitudinally therein.
6. A compound curved member; a reproducer arm having a neck portion detachably threaded thereto; said neck portion being received within the lower curve of the compound curved member; and a horn having a curved neck received within the upper curve of the compound curved member to have a longitudinal free movement therein; said arm and horn being supportable in various positions.
7. A curved tubular member; and a reproducer arm having a curved neck detachably threaded thereto and correspondingly curved with regard to the curved tubular member, received and supported within the curved tubular member to have longitudinal vertical telescopical movements therein.
- 35 8. A curved tubular member; and a reproducer arm having a curved neck detachably threaded thereto and correspondingly curved with regard to the curved tubular member, received and supported within the curved tubular member to have longitudinal vertical movements therein; said arm being supportable in various positions.
9. In a talking machine; a compound curved member; a horn support having a detachable connection therewith; and a re-
- producer arm and horn having curved necks telescopically received by said compound curved tubular member.
10. A quarterly curved member; a reproducer arm having a swiveled member correspondingly curved; said members being telescopically united.
11. A quarterly curved member; a horn having a swiveled member; said members being telescopically united whereby the horn may be raised or lowered.
12. An amplifier; comprising a compound curved tubular member; and telescopically movable free portions correspondingly curved and supported from either end of the member.
13. An amplifier; comprising a compound curved tubular member; telescopically movable free portions correspondingly curved and supported from either end of the member; and means permitting one of the free portions to move concentrically with regard to the member.
14. An amplifier; comprising a compound curved tubular member; telescopically movable free portions correspondingly curved and supported from either end of the member; said free portions being supportable in various raised or lowered positions.
15. An amplifier; comprising a compound curved tubular member; telescopically movable free portions correspondingly curved and supported from either end of the member; means permitting one of the free portions to move concentrically with regard to the member; said free portions being supportable in various raised or lowered positions.
